UNITED STATES PATENT OFFICE.

CARL AUGUST MÜLLER, OF WITZENHAUSEN, GERMANY.

CYLINDER-LOCK.

1,114,709.

Specification of Letters Patent. Patented Oct. 20, 1914.

Application filed August 9, 1912. Serial No. 714,236.

To all whom it may concern:

Be it known that I, CARL AUGUST MÜLLER, a subject of the German Emperor, residing at Witzenhausen, Germany, have invented certain new and useful Improvements in Cylinder-Locks, of which the following is a specification.

The pin tumblers of safety locks with rotating cylindrical plug hitherto used, in 10 which the said tumblers controlled by springs engage from the casing with the rotating body and are adjusted or set by the key by means of drivers, were formerly made either in such a way that after the 15 destruction of the parts by means of which they were set and which were of the same diameter, they could enter their guide holes as their travel was unlimited, so that the security of the lock was destroyed, or they 20 were partly provided with a limitation of the travel which however was not suitable for insuring the safety of the lock. As is well known, attempts are made to force open the locks by boring the locking parts. 25 If the tumblers lock under the action of intermediate parts, it will always be found that they will be destroyed by boring. Tumblers provided with a strengthened head or the like, the travel of which is thus 30 partly limited, also enable the lock to be easily opened by simply boring the part in question. This disadvantage is obviated by the present invention by the tumblers being made of such shape that both after the 35 destruction of the parts adjusting or setting the same, as well as of their locking parts proper, they still continue to lock the lock independently. Only with pin tumblers formed throughout the whole of their 40 length for independent locking, is it possible to obtain a lock giving a real security, as they oppose the greatest possible obstacle to any attempts at destruction. Such tumblers of course increase considerably the 45 safety of the lock.

A construction of a safety lock provided with tumblers of such construction is shown in Figures 1 and 2 of the accompanying drawing, while Figs. 3 to 9 show modified 50 constructions.

The rotating body *a* is locked relatively to the casing *b* by the spring controlled followers *c* in the well-known manner, the followers being arranged for operation by 55 means of drivers *d* operated by the key, one or more locking bodies or followers and

drivers being provided as desired. In order to prevent the followers from passing directly into their guide conduit after the destruction of the drivers *d* opposite the same, 60 whereby the locking would be destroyed, they are constructed according to this invention so that they have throughout the whole of their length a limited travel. This is done according to Figs. 1 and 2 by 65 the followers being given throughout the whole of their length, a greater diameter than that of the drivers and their guide conduit. If it is attempted to force the lock open by boring away the locking portion 70 between the body *a* and the casing *b*, the tumbler will at once advance and lock again, which is not the case for instance in tumblers provided with a head.

The increase of diameter relatively to that 75 of the opposite parts, extends the whole length and the whole circumference of the tumblers *c*, but it could also extend only to a portion of the circumference, the widened portion being given the shape of flanges *e* 80 (Fig. 3). It can also be obtained by separate auxiliary bodies, for instance balls *f* (Figs. 4-8), mounted in separate recesses of the followers, the mounting on the two opposite sides being if desired alternate as 85 shown in Fig. 5. The mounting can also be in a helical line, as shown in Fig. 6. The balls can also pass through the followers, for instance be arranged in perforations of any desired arrangement (Figs. 7 and 8). 90 More particularly, when balls as hard as glass are used, these followers offer considerable resistance to boring, because on one ball and the locking point of the tumbler being bored away, another ball at once 95 takes over the limiting of the travel of the tumbler by falling after it. The followers themselves can then be constituted by balls, namely of a greater diameter than that of the opposite guide holes (Fig. 9). The 100 balls could be connected together for instance by a pin passing through them. The construction can vary, and the same applies to the cross-section of the tumblers. Thus for instance the widening of the tumblers 105 can be obtained by insertion of metal pieces as hard as glass (for instance ledges *e* in Fig. 3).

What I claim as my invention and desire to secure by Letters Patent is:—

1. In a tumbler lock, a cylindrical casing, a cylinder rotatable within said casing, in-

termediate key-operated parts extending in recesses in the cylinder, and tumblers in said casing having throughout their length a larger diameter than the intermediate parts, and shoulders in the recesses of the cylinders adapted to be engaged by said tumblers.

2. In a tumbler lock, a cylindrical casing, a cylinder rotatable within said casing, intermediate key-operated parts extending in recesses in the cylinder and a plurality of rows of balls in said casing of larger di-

ameter than the intermediate parts, and shoulders in the recesses of the cylinders adapted to be engaged by said rows of balls.

In testimony whereof I have signed my ¹⁵ name to this specification in the presence of two subscribing witnesses.

CARL AUGUST MÜLLER.
